UNITED STATES PATENT OFFICE.

BURR B. BLOOD, OF CHICAGO, ILLINOIS, ASSIGNOR TO GEORGE HEIDMAN AND NORMAN A. STREET, BOTH OF CHICAGO, ILLINOIS.

PHONOGRAPH.

1,313,250.

Specification of Letters Patent.

Patented Aug. 19, 1919.

Application filed October 10, 1917. Serial No. 195,702.

To all whom it may concern:

Be it known that I, BURR B. BLOOD, a citizen of the United States, and a resident of Chicago, in the county of Cook and State 5 of Illinois, have invented new and useful Improvements in Phonographs, of which the following is a description, reference being had to the accompanying drawing, which forms a part of my invention.

10 My invention relates more particularly to the tone-chamber or amplifier of a phonograph; the construction being adapted to give the reproduced tones or sounds their natural tone quality and enable them to be 15 presented in a clear, distinct manner and with volume commensurate with the original production or selection.

The invention also contemplates a construction which enables the tones to be modified 20 so as to reduce the volume when desired, and also to control and so direct the tones of certain selections as to give them the natural tone quality or effect of the original selection, as will be more readily 25 understood from the detailed description of the accompanying drawing, wherein:—

Figure 1 is a vertical sectional view of the upper portion of a phonograph, in other words the tone-chamber portion of the cabinet, the turn-table and tone-arm; the reproducer-carrying portion of the latter being broken away.

Fig. 2 is a cross sectional plan view taken on the line 2—2 of Fig. 1 looking in the 35 direction of the arrows.

Fig. 3 is a detail sectional view of the tone or sound-controlling means.

In the specific exemplification, as disclosed in the drawing, the phonograph cabinet 40 is shown composed of wood and made in the usual manner, preferably rectangular in cross section so as to provide sufficient space for my improved tone-chamber; the outer or main cabinet portion being shown 45 at 10 in the drawing.

The cabinet comprises the usual top or motor-supporting board 11 from which the motor is suspended, the latter being diagrammatically indicated at 12; the top or 50 motor-supporting board 11 being at some distance removed from the bottom board 13; thus providing a chamber within which the motor is suspended and within which chamber my improved amplifying means 55 are located.

The front of this chamber is provided

with a grille or open-work panel 14 in order to permit the tones or sounds to issue from the tone-chamber or amplifying means. The usual tone-arm, indicated at 15, is suitably mounted in the orifice of the vertically disposed throat or tube 16 whereby the tones or sounds are conveyed from the reproducer (not shown) mounted at the end of the tone-arm 15 through the arm 15 into the throat or tube 16 and thence out through my improved amplifier or tone-chamber. The tone-chamber is preferably shown bell-shaped in horizontal cross-section, see Fig. 2; the chamber being provided with the bent side walls 17, 17 preferably of thin wood or veneer bowed so as to flare toward the front of the cabinet where the grille 14 is located; the front ends of the side walls 17 being secured in any 75 suitable manner to the side walls 10 of the main cabinet. The rear ends of the side walls 17, 17 are secured in a suitable manner, preferably in suitable grooves formed in the forwardly presented lugs or portions at the 80 ends of a transversely disposed sleeve or tubular base-portion 18 of the throat-member 16. The throat 16 and transversely disposed tubular portion 18 may be formed integral and of suitable metal; with the 85 throat-portion 16 communicating centrally with the transversely disposed portion 18, as very clearly shown in Figs. 2 and 3. The portion 18 is made of a length sufficient to correspond with the width of the rear end of 90 the tone-chamber 19 and is shown open-sided toward the tone-chamber; with one end of the transversely disposed tubular portion 18 shown closed while the other end is provided with a removable nut or cap- 95 portion 20 shown screwed into place, see Figs. 2 and 3.

The removable end or cap-portion 20 enables the insertion of the tubular valve or member 21 which is preferably made of 100 suitable metal and provided with an opening at 22 at a point intermediate of its ends. The opening is somewhat elongated and disposed transversely of valve 21 so as to remain in register with the throat 16 when 105 the valve is partially rotated about its longitudinal axis. Adjacent the ends of the valve or sleeve 21, and on the side disposed toward the tone-chamber 19, it is provided with openings 23, 23 which register with the 110 rear end of the tone-chamber 19, at opposite sides thereof, as clearly shown in Fig. 2.

The tone-chamber 19 is provided with a top 24, see Fig. 1, arranged in the upwardly sloping manner from rear to front as indicated in Fig. 1. Adjacent the bottom of the tone-chamber 19, and intermediate of its sides, I provide an auxiliary chamber 25, shown oblong or egg-shape in cross-section in Fig. 2. The side walls of the chamber 25 are preferably formed by bowing a continuous strip of thin wood or veneer into the shape shown; the ends thereof being secured in any suitable manner, as for example in the lugs 26 formed on the forward side of the transversely disposed sleeve-portion 18, see Figs. 2 and 3. The auxiliary tone-chamber 25 is provided with a suitable top 27 and a bottom 28; the top 27 being preferably slightly bowed, as indicated in Fig. 1; the top and bottom being maintained in proper relation with each other by a suitable post 29, see Fig. 1, the latter being preferably composed of wood and arranged at a suitable intermediate point in the auxiliary chamber 25. This post 29 also enables vibrations to be transmitted therethrough from top to bottom, and vice versa. The forwardly presented end of the auxiliary chamber 25 is provided with a suitable number of openings, preferably shown S-shape, at 30, in Fig. 1. These openings permit any tones or sounds that are transmitted into the auxiliary chamber 25 to find egress through the forward part of the chamber, into the main tone-chamber 19 and thence through the grille 14.

The central elongated opening 22 in the tubular member or valve 21 is made of sufficient length to enable the valve to be rotated and permit the opening 22 to be in register with the throat 16 and with the rear end of auxiliary chamber 25. The tubular member or valve 21 is provided with a suitable rod 31, of a length to extend through the side of the main cabinet, as shown in Fig. 2; the outer end being provided with a suitable grasp or thumb-nut 32 to enable the operator to rotate the rod 31 and therefore also tubular member or valve 21 so as to either bring the openings 23, 23 of the tubular member or valve 21 into register with the rear end of the main tone-chamber 19 and opening 22 into register with the throat 16, or by further rotation of the tubular member or valve 21 move the openings 23, 23 out of register with the main tone-chamber 19 while the end of the elongated opening 22 is left in register with the throat 16 and the other end of the opening moved into communication with the auxiliary tone-chamber 25. With the openings 23 in register or communication with the main chamber 19, all tone waves or sounds are transmitted into chamber 19; while movement of valve 21, so as to have opening 22 communicate with chamber 25, causes all tones or

sounds to pass from the throat 16 into the auxiliary chamber 25, thereby modifying the tones or sounds which are being reproduced.

My auxiliary tone-chamber 25 is more especially intended to be employed during the reproduction of selections rendered by string instruments, and more especially violin; the auxiliary chamber being adapted to give the reproduced tones or sounds the natural or violin tone. This effect is due to the construction of the auxiliary chamber whose walls are composed of suitable thin wood or veneer, with the top and bottom separated by the sound post 29, as previously described.

As is apparent from the construction shown and described, all of the tones or sounds may be transmitted through the openings 23, 23, into the main tone-chamber 19, to wit on opposite sides of the auxiliary chamber 25, as is the case when the tubular member or valve 21 is in the position shown in all of the figures. With the valve 21 in the position shown in the drawing, communication with the auxiliary chamber 25 is cut off by the wall 21^a of the tubular member or valve 21. On the other hand, the tones or sounds may all be transmitted through auxiliary chamber 25 and thence into the forward portion of the main tone-chamber 19 by a proper or forward rotation of tubular member or valve 21 so as to throw the openings 23, 23 out of register with the rearward end of the main tone-chamber 19 and move the elongated opening 22 of the tubular member or valve into register with the rear end of auxiliary chamber 25, with one end thereof still remaining in register with the throat or opening 16.

I have shown and described a tone-chamber or amplifier which greatly enhances the tone qualities and whereby the reproduced sounds or tones are obtained in a natural or life-like manner and at the same time permitting the tones to be produced with the desired volume, without, however, in any way interfering with the tone quality.

I have shown and described my improved tone-chambers as preferably composed of wood and of increasing dimensions from rear to front; the side walls being given a suitable curvature so as to provide curved, uninterrupted passages of gradually increasing dimensions, which permit the gradual expansion of the sound waves. The invention, however, may have expression in somewhat different mechanical form without departing from the spirit of the invention.

For example, in Fig. 1, I have shown the integral front and side walls 25^a of the auxiliary chamber 25 extending beyond the top 27 of said chamber and throughout the vertical depth of the main tone-chamber 19. This construction is especially employed

- where the space or chamber intermediate of the motor-supporting board 11 and the bottom 13 is not of sufficient vertical depth to permit the motor to be suspended above 5 the top 24 of the tone-chamber 19. The top 24, in such constructions, is cut away to provide an opening for the motor, as shown, while the integral front and side wall 25* extends into the cut-away portion in the top 10 24 of the tone-chamber so as to incase or house the motor 12 and prevent motor noises passing into the tone-chamber proper; and with the top 27 such noises cannot pass into the auxiliary tone-chamber 25.
- 15 What I claim is:—
1. A phonograph, comprising a main casting provided with a sound-conveying conduit arranged in communication with the tone-arm or reproducer-carrying member, 20 while the opposite end of the conduit terminates in a laterally disposed sleeve-portion provided with openings in the side disposed toward the front of the phonograph, a tubular member or valve rotatably mounted 25 in said sleeve-portion and provided with openings adjacent both ends thereof adapted to register with the openings in the forward side of said sleeve-portion and having an opening intermediate of its ends adapted 30 to register with the sound-conveying conduit and with an opening in the front side of the sleeve member and intermediate of its ends, and a pair of tone-chambers, one of which is adapted to receive the tones 35 through the openings adjacent the ends of the valve, while the other is adapted to receive the tones through the opening arranged intermediate of the ends of the valve.
  2. In a phonograph, provided with a 40 sound-conveying conduit, a tone-chamber provided with walls converging toward said conduit and adapted to be in communication with the lower end thereof, an auxiliary tone-chamber arranged centrally within the 45 first-mentioned tone-chamber and adapted to be in communication with said conduit, said auxiliary chamber being arranged in communication with the forward end of the main chamber, and means located in said 50 conduit whereby the tones or sounds are transmitted either into the main tone-chamber or into said auxiliary tone-chamber.
  3. In a phonograph, a sound-conveying conduit terminating at its end in a laterally 55 disposed sleeve-portion provided with openings in one side wall thereof, a main tone-chamber whose walls converge toward said sleeve and are secured thereto, an auxiliary tone-chamber mounted within the first-mentioned tone-chamber with its walls converging 60 toward said laterally disposed sleeve and secured thereto at points intermediate of the ends thereof, the openings in said sleeve-portion normally communicating with both chambers, and a tubular valve rotatably mounted in said sleeve-portion and provided with a plurality of openings adapted to effect the communication between said sleeve-portion and the two tone-chambers so as to compel the sound-waves or tones to either 65 pass directly into said first-mentioned tone-chamber or into the second or auxiliary tone-chamber.
  4. In a phonograph, provided with a sound-conveying conduit, a tone-chamber 70 provided with curved side walls converging toward said conduit and normally in communication therewith, an auxiliary tone-chamber arranged within the first-mentioned chamber and adapted to be in communication with said conduit, said chamber having side walls bowed into oval shape, with openings in the forward end thereof, and means located in said conduit whereby the tones or sound waves are transmitted either into the 75 first mentioned chamber or into said second mentioned chamber.
  5. In a phonograph, provided with a sound-conveying conduit terminating at its end in a transversely disposed sleeve-portion 80 open on its side toward the front of the phonograph, a tone-chamber provided with walls converging toward and connected to said sleeve-portion, said chamber being open at its front, a second chamber located in the 85 first chamber and in communication with said sleeve-portion, the side wall of said second chamber being bowed to provide a spheroidal or substantially egg-shape chamber in cross-section, a post arranged intermediate of the top and bottom of said chamber whereby vibrations may be transmitted from one to the other, the front end of said chamber being provided with openings, and a tubular valve located in said sleeve-portion whereby the sound-waves are transmitted from the conduit either into the first-mentioned tone-chamber or into the second-mentioned tone-chamber.
  6. In a phonograph, a tone-chamber provided with rearwardly converging top and side walls, a second tone-chamber located within the first chamber, the sides of said second chamber being formed of a continuous strips of thin wood bowed into spheroidal 95 shape in cross-section, with the front side thereof provided with sound-outlets, while the top wall of said second chamber is bowed, and vibration-transmitting means secured to the top and bottom within said second chamber.
